(57) **CLAIM**

The ornamental design for a sound deadening panel for use in transportation units, as shown and described.

DESCRIPTION

FIG. 1 is a top, perspective view of the sound deadening panel for use in transportation units showing my new design; FIG. 2 is an enlarged, front elevation view thereof; FIG. 3 is an enlarged, top plan view thereof; FIG. 4 is an enlarged, side elevation thereof; FIG. 5 is an enlarged, rear elevation view thereof; and, FIG. 6 is an enlarged, partial cross-sectional view thereof taken at 6-6 of FIG. 2.

The broken lines are for the purpose of illustrating the indicator of the cross-section and the bounds of the claimed design and form no part of the claimed design.
